United States Patent Office

Des. 214,481

Patented June 17, 1969

214,481

MILKING APPARATUS

Robert J. Shulick, St. Charles, and Harold V. Swanson,
Downers Grove, Ill., assignors to Babson Bros. Co.,
a corporation of Illinois

Filed June 20, 1968, Ser. No. 12,444

Term of patent 14 years

Int. Cl. D15—03; D30—99

U.S. Cl. D98—1

FIGURE 1 is a side elevational view of a milking apparatus embodying our new design;

FIGURE 2 is a side elevational view looking to the left in FIGURE 1;

FIGURE 3 is a top plan view looking down from the top of FIGURE 1;

FIGURE 4 is a side elevational view opposite that of FIGURE 1;

FIGURE 5 is a side elevational view opposite that of FIGURE 2; and

FIGURE 6 is a bottom plan view looking up from the bottom of FIGURE 1.

We claim:

The ornamental design for a milking apparatus, as shown and described.
